United States Patent Office

Des. 193,004
Patented June 12, 1962

193,004

TAPE DRIVE UNIT OR SIMILAR ARTICLE

Henry Dreyfuss, South Pasadena, Calif., and Robert A. Pendleton, Winchester, and Richard B. Lawrence, Dedham, Mass., assignors to Minneapolis-Honeywell Regulator Company, Minneapolis, Minn., a corporation of Delaware

Filed Sept. 8, 1960, Ser. No. 62,068

Term of patent 14 years

(Cl. D26—5)

FIG. 1

FIG. 2

FIGURE 1 is a front perspective view of a tape drive unit or similar article embodying our new design.

FIGURE 2 is a rear perspective view of the same.

Portions of the drawing are stippled to indicate contrast in appearance and portions are diagonally lined to indicate transparency.

The dominant features of the design reside in the relatively deep, inwardly tapered vertical columns terminating at the horizontal window which define a pair of deep, outwardly tapered tape-loop chambers. The dominant features of the design further reside in the clean horizontal lines above the lower window edge juxtaposed with the vertical lines below said window edge, as well as in the position of the magnetic tape head relative to the tape reels and in contact with the horizontal cover panel under the window.

We claim:

The ornamental design for a tape drive unit or similar article, as shown and described.
